HOLLOW STEM CRYSTAL BEER GOBLET

William A. Meier, Rochester, Pa.

Application February 5, 1948, Serial No. 144,297

Term of patent 14 years

(Cl. D36—8)

To all whom it may concern:

Be it known that I, William A. Meier, a citizen of the United States of America and a resident of Rochester, in the county of Beaver and State of Pennsylvania, have invented a new, original, and ornamental Design for a Hollow Stem Crystal Beer Goblet, of which the following is a specification, reference being had to the accompanying drawing, forming a part thereof.

In the accompanying drawing:

Fig. 1 is a side elevational view of a hollow stem crystal beer goblet showing my new design;

Fig. 2 is a top plan view; and

Fig. 3 is a vertical sectional view thereof on a reduced scale.

I claim:

The ornamental design for a hollow stem crystal beer goblet, as shown.

WILLIAM A. MEIER.
